(57) **CLAIM**

The ornamental design for a bottle, as shown and described.

DESCRIPTION

FIG. 1 is a perspective view of the first embodiment of a bottle;
FIG. 2 is a front view thereof;

FIG. 3 is a rear side view thereof;

FIG. 4 is a right side view thereof;

FIG. 5 is a left side view thereof;

FIG. 6 is a top view thereof;

FIG. 7 is a bottom view thereof.

FIG. 8 is a perspective view of the second embodiment of a bottle;

FIG. 9 is a front view thereof;

FIG. 10 is a rear side view thereof;

FIG. 11 is a right side view thereof;

FIG. 12 is a left side view thereof;

FIG. 13 is a top view thereof; and,

FIG. 14 is a bottom view thereof.

The broken line showing of portions of the bottle is included
for the purpose of illustrating environmental structure and
forms no part of the claimed design.

1 Claim, 14 Drawing Sheets
